UNITED STATES PATENT OFFICE.

FREDERICK F. RICHE, OF TROY, NEW YORK.

MALE URINAL-BAG.

1,389,531.

Specification of Letters Patent. Patented Aug. 30, 1921.

Application filed July 29, 1919. Serial No. 313,999.

To all whom it may concern:

Be it known that I, FREDERICK F. RICHE, a citizen of the United States, residing at Troy, in the county of Rensselaer and State 5 of New York, have invented new and useful Improvements in Male Urinal-Bags, of which the following is a specification.

This invention has reference to a male urinal bag and has for its primary object to 10 produce a device of this character which may be worn with ease and comfort by a patient, either when reclining or reposing, or when in an erect active position, without danger of leakage or damage to the person 15 or clothing of the wearer.

A further object is to produce an article of this character comprising a shield which is strapped or otherwise secured to the person of the patient and a bag which is removably attached to the shield whereby the latter may be detached from the shield for 20 emptying, or cleaning, or when not desired for immediate use without necessitating the removal of the shield.

25 Other objects and advantages will appear as the nature of the invention is more fully understood, reference being had to the drawings, which accompany and form part of this specification.

30 In the drawings:

Figure 1 is a view of the improvement.

Fig. 2 is a sectional view through the mouth of the bag and through the shield.

Fig. 3 is a front elevation of the shield.

35 Fig. 4 is a rear elevation thereof.

Fig. 5 is a side elevation of the same.

Fig. 6 is a sectional view on the line 6—6 of Fig. 3.

40 My improvement comprises a soft rubber shield 10 and a soft thin rubber bag 11, which is detachably attached to the shield.

The bag 11 has its edges at the mouth portion 12 thereof turned over a cross sectionally round rubber ring 13, the said edges 45 being secured to the bag proper, thus providing a housing for the ring.

The shield 10 comprises a member which is round in plan and which is provided at 50 its inner edge with spaced projecting tabs 14 to which are connected the adjustable straps 15 that secure the shield on the person of the user.

The shield has a boss-like protuberance on one face thereof. The face 18 of the boss 17

is arranged at a downward angle or, in other words, the upper edge of the boss is spaced farther from the inner face of the shield than is the lower edge thereof. The boss is round in plan and is provided with a peripheral continuous groove 19 that is arranged in a line with or that is parallel to the inclined face of the said boss. This groove 19 is designed to receive the elastic ring 13 in the mouth of the bag 11. The groove is of a desired depth so that the walls thereof will 55 be firmly gripped by the ring, or more strictly speaking the ring will cause the portion of the bag-mouth within which it is pocketed to be compressed against the walls of the groove so that the bag is firmly supported by the shield. The bag may, of course, be readily removed for emptying, cleaning or when not desired for immediate use without necessitating the removal of the shield.

75 The outer flat face of the shield has a cup shaped depression 22 arranged opposite the boss and provided with a central round opening 20 that passes through the boss. The wall provided by the opening in the 80 boss provides the said boss with what I will term a lip and which is indicated by the numeral 21.

The opening 20 is designed to receive therethrough the organ of the patient and is 85 of sufficient area to freely receive the same and permit the inner straight face of the shield snugly contacting the abdomen. The lip 21 contacts with the organ but not with sufficient pressure to inflict injury thereto. 90 The lip serves as a dam or obstructing element to prevent a passage of the urine from the bag through the opening in the shield when the patient is in a lying position, and it is thought from the foregoing description, when taken in connection with the drawings that the construction, method of application, advantages and simplicity of the construction will be understood and appreciated without further detailed description. 100

Having thus described the invention, what is claimed as new, is:—

A male urinal bag of the class described comprising a soft compressible rubber shield, a thin rubber bag detachably attached to said shield, a pair of spaced projecting tabs provided on the inner edge of

said shield, a rubber ring being secured to the bag proper which forms a housing for said ring, a pair of straps secured to said spaced projecting tabs for attaching said bag to the user, a boss-like protuberance formed on one face of said shield, the outer face thereof being arranged at a downward

angle, a peripheral continuous groove being arranged in parallel relation to said outer face of said boss, and an annular lip being 10 provided on said boss.

In testimony whereof I affix my signature.

FREDERICK F. RICHE.
